CLAIM

The ornamental design for a docking station, as shown and described.

DESCRIPTION

FIG. 1 is a front perspective view of a docking station showing a new design thereof;
FIG. 2 shows a top plan view thereof;
FIG. 3 shows a right elevation view thereof;
FIG. 4 shows a left elevation view thereof;
FIG. 5 shows a front elevation view thereof;
FIG. 6 shows a rear elevation view thereof; and,
FIG. 7 shows a bottom plan view thereof.

All broken lines in the drawings depict portions of the docking station that form no part of the claimed design.
